UNITED STATES PATENT OFFICE.

EDMUND C. MORGAN, OF RICHMOND HILL, NEW YORK.

APPARATUS FOR MINING.

Application filed September 16, 1918. Serial No. 254,266.

To all whom it may concern:

Be it known that I, EDMUND C. MORGAN, a citizen of the United States, residing at Richmond Hill, New York city, in the county of Queens and State of New York, have invented certain new and useful Improvements in Apparatus for Mining, of which the following is a specification.

This invention has for its object the provision of an improved method for mining together with apparatus to be used in connection with the improved method which shall also be of improved construction and operation.

The invention is exemplified in the combination and arrangement of parts of the apparatus shown in the accompanying drawings and described in the following specification, and in the steps of the process described in the specification. The invention is more particularly pointed out in the appended claims.

In the drawings—

Fig. 1 is a fragmentary horizontal section through a portion of a mine showing one arrangement of entries and chambers in connection with which my improved method may be employed.

Fig. 2 is a view similar to Fig. 1 but showing the application of the method to the whole mine.

Fig. 3 is a top plan view of apparatus forming a part of the present invention.

Fig. 4 is an elevation of the apparatus shown in Fig. 3.

Figs. 5, 6, 7 and 8 taken together form a top plan view of the apparatus shown in Figs. 3 and 4 but on a much larger scale.

Figs. 9, 10, 11 and 12 taken together form a side elevation of the apparatus shown in Figs. 5, 6, 7 and 8.

Figs. 13, 14, 15 and 16 taken together form a longitudinal vertical sectional view of the apparatus shown in Figs. 5 to 12, inclusive.

Fig. 17 is a top plan view of the winding reel and carriage forming a part of the present invention.

Fig. 18 is a side elevation of the same.

Fig. 19 is a vertical section of the apparatus shown in Fig. 17.

Fig. 20 is a diagrammatic plan view of a mine chamber showing the application of the apparatus shown in Figs. 17, 18 and 19.

Fig. 21 is a longitudinal vertical sectional view, and

55

Fig. 22 is a transverse vertical sectional view of the portion of the mine chamber shown in Fig. 20.

Fig. 23 on the sheet of drawings containing Figs. 18 and 19 is an enlarged view of the insulating sleeve for a trolley wire.

In the mining of coal or similar material by machinery where the machines used are necessarily expensive to build, it is desirable that the machines be kept in operation

65

as nearly constantly as possible, and that the mining operation be concentrated as much as possible so that the work may be carried

70

on uninterruptedly and with a minimum amount of waste of time and energy. The process of mining forming a part of the

75

present invention may be carried out by various forms of mining machinery which perform different steps in the process, part of the steps being performed by a machine of

75

one type and other steps being performed by machines of other types, the entire process being carried forward by the different machines working in cooperation

80

with one another to secure the rapid and economical removal of the desirable material from the mine vein. In Fig. 2 of the

85

drawings, which illustrates a mine laid out for mining according to the present invention, the numeral 25 designates a mine shaft

85

from which the coal is raised to the earth's surface or a mine tipple in case the mine is such that the loaded cars may be brought to

90

the surface without the use of a shaft. Leading from the shaft 25 along the main entry of the mine is a plurality of mine tracks 26

95

along which the loaded cars are brought to the shaft and the empty cars are returned to the mine chambers. Leading laterally from

95

the main entry are a series of sets of butt entries 27, 28 and 29 into which spurs from the main tracks 26 lead. The rooms from which

100

the coal is mined are arranged transversely to the spur tracks in the entries 27, 28 and 29, as shown at 30 in Fig. 2 of the drawings. The rooms 30 are connected to the entries

105

27, 28 and 29 by short transverse entries 31 forming necks to the various rooms 30. The room necks 31 are preferably arranged to intersect the entries 27, 28 and 29 at an oblique

angle so that tracks 32 in the room necks may

be readily joined to the tracks in the entries 27, 28 and 29. It may also be found convenient to extend the short transverse entries 31 entirely across the entries 27, 28 and 29 so that 5 they may be connected with rooms at both sides of the three parallel entries. This arrangement is clearly illustrated in Fig. 1 of the drawings and affords ample track facilities necessary for concentrated operation 10 where a number of machines are being used that must be shifted from one room to another and where facilities must be provided for transporting the large amount of coal excavated by continuous operation.

15 In Fig. 1 of the drawings a series of rooms 30 are shown which are separately designated by the reference letters A, B, C and D, there being two rooms designated by each of the letters C and D. Work will be carried 20 on simultaneously in the six rooms designated by the letters referred to. In the room A which is the foremost room of the series, a machine E will operate to undercut the material to be mined. This machine may be of any well known construction, one form of machine adapted for the purpose being shown in my copending application, Serial No. 250,844, filed August 21, 1918. While the material is being undercut 25 in the room A, the material previously undercut in the room B is being blasted down preparatory to loading. A car F is shown in this room for transporting the various necessary blasting material into and 30 out of the chamber. In the two rooms C loading machines G are shown in operation for loading the material previously blasted down. These loading machines may be of any well known and approved construction, 35 one form of machine adapted for this purpose being shown in my application, Serial No. 186,118, filed August 14, 1917. In the rooms D from which the broken down material has been previously removed, mechanism 40 designated by the letter H is shown in position preparing the rooms for a second series of mining operations. The mechanism for this purpose is illustrated in Figs. 3 to 16, inclusive, of the drawings in the present application. In each of the rooms A, B, C and D is shown a trolley wire carriage and reel support which is illustrated in Figs. 15 to 21, inclusive, of the present application. In carrying out the process, it is 45 usually desirable to use two of the loading machines G and two sets of mechanism H for each of the machines E for the reason that one machine E can usually undercut the material in two rooms in the time required for 50 one of the machines G to load the material blasted down in a single room. In order that the machines may be kept continually in operation, it is of course necessary to shift them from one room to another so that they 55 may operate in proper sequence in the va-

rious rooms. For this shifting of the machines from one room to the other, the track 27 adjacent the rooms being worked, is preferably employed while the remaining tracks 28 and 29 are left free for the transportation 70 of the coal cars to and from the rooms being worked. The entries 27, 28 and 29 and the tracks therein are used for working the rooms 30 on both sides of the entries so that the same material and labor for laying 75 tracks is available for removing the coal from both sets of rooms or chambers. The rooms may be worked on both sides of the entries simultaneously or the rooms along one side may be worked for a considerable 80 distance, and subsequently the rooms on the other side excavated.

The machines for undercutting and loading the material are comparatively heavy and require correspondingly heavy tracks 85 upon which to operate. These tracks are preferably built up in sections before they are brought into the mine chambers and it is a part of the function of the machine shown at H in Fig. 1 of the drawings to 90 bring the track sections into place and position them on the mine floor. During the undercutting and loading operations the tracks are not changed in any way but the excavating of the material is advanced as 95 far as possible from the tracks previously laid in the chambers and then the machines are withdrawn from the chambers to permit extension of the track so that a second series of operations may be carried out. 100 At the same time that the track is being extended mine props are set in the chamber and the trolley line extended so that it may furnish power for the next series of operations. The machine H which is used for 105 advancing the track and trolley line and for setting props is the one illustrated in Figs. 3 to 16, inclusive. It consists of a forward truck 35 and a rear truck 36 connected by a coupler 37. The forward truck is best illustrated in Figs. 7, 8, 11, 12, 15 and 16 and 110 comprises the usual truck wheels 38 and springs 39 for supporting the truck body. The truck body may be of skeleton construction having angle side bars 40 connected by cross rails 41. Brackets 42 extend laterally from the side rails 40 and carry upright side plates 43. A series of track sections may be carried on the truck body, as shown in Figs. 7, 8, 15 and 16, each section comprising 115 a pair of rails 44 and cross ties 45. Pivotally mounted in bearings 46 carried by the side rails 40 near the forward end of the truck is a bar 47 having arms 48 rigidly secured to its opposite ends. The arms 48 are curved downwardly at their extremities and carry a plate 49 which may be adjusted vertically about the pivot bar 47 and held in adjusted positions by a rack 50 arranged 120 to cooperate with a lever arm 51 which 125

forms an extension of one of the arms 48. The plate 49 is for the purpose of guiding the track sections onto and off of the truck and is adjusted about the pivot 47 so that its height may be regulated to correspond to the upper surface of the pile of tracks already on the truck.

- The rear truck 36 is supported on forward truck wheels 52 and rear truck wheels 53.
- 10 The forward truck wheels 52 are provided with springs 54 but the rear truck wheels are preferably journaled in fixed bearings 55 rigidly supported by a plate 56 which forms the bottom or main body plate for the truck.
- 15 Angle bars 57 may be secured to the forward portion of the bed plate 56 for strengthening the frame of the truck. Channel plates 58 are connected with the upper face of the plate 56 and extend transversely of the truck and 20 an end plate 59 extends transversely of the truck at its forward end and is secured to the plate 56 by angle irons 60. A pair of angle bars 61 are supported by the upper edges of channel bars 58 and by an 25 angle bar 62 on the plate 59 as shown in Fig. 14. The channel bars 61 are arranged near one another but spaced slightly apart at the longitudinal center of the truck and are bent downwardly at their rear ends and 30 secured to the bed plate 56, as shown in Fig. 13 at 63 at the rear end of the truck. A motor 64 is mounted on the upper face of the bed plate 56 and has a pinion 65 meshing with a gear 66 rigidly secured to the end of 35 a sleeve 67 which is mounted to rotate on the axle 68 to which the rear truck wheels 53 are rigidly secured. The sleeve 67 may be clutched to the axle 68 by a sliding clutch 69 feathered to the axle and operated by a lever 40 70. When the clutch 69 engages the sleeve 67, it will be apparent that rotation of the motor 64 will drive the truck wheels 53 to propel the truck upon the mine track. The end of the axle 68 is provided with a spiral 45 gear 71 which drives a similar gear 72 secured to the end of a shaft 73 journaled in a bearing 74 mounted on the bed plate 56. The forward end of the shaft 73 is geared to the axle 75 which carries the front truck 50 wheels 52 by spiral gearing similar to that of the opposite end of the shaft and enclosed in a casing 76. The shaft 73 is provided with a universal joint 77 to permit of the relative movement of the truck and axle 75 55 as the spring 54 is compressed and expanded.
- A winding drum 78 is mounted on a shaft 79 journaled in bearings 80 secured to the upper face of the bed plate 56 and may be clutched to the shaft 79 to rotate therewith 60 by a friction clutch 81 operated by a lever 82. A gear 83 is secured to the shaft 79 and meshes with a pinion 84 upon the sleeve 67 so that the gear 83 is continuously driven by the motor 64 when the motor is operated and 65 the drum 78 may be clutched to the shaft 79

to rotate with the gear 83 when it is desired to wind the cable 85 upon the drum. This cable 85 extends forwardly between guide pulleys 86 mounted on the upper face of a plate 87 at the forward end of the truck. 70 The cable may be provided with a hook 88 or other fastening device at its outer end.

A saw guard or housing 89 is secured to the upper face of the bed plate 56 and to the inner faces of the longitudinal angle bars 61, 75 and a circular saw 90 is journaled at 91 between the sides of the guard. The saw 90 is driven by a belt 92 which passes over a pulley 93 on a shaft 94 which is provided with a pinion 95 meshing with the gear 66 80 which drives the sleeve 67. The belt 92 passes loosely over its pulleys so that ordinarily the belt will slip on the pulley and motion will not be transmitted to the saw 90. A belt tightener comprising a lever 96 85 and an idler 97 arranged to engage the belt 92 is provided for placing sufficient tension in the belt 92 to drive the saw 90 when it is desired to do so. The lever 96 is connected by a link 98 to a 90 rocker arm 99 and lever 100 by which the tightener may be moved to cause the saw to rotate. A ratchet bar 101 is provided for holding the lever 100 in adjusted positions. A saw carriage 102 extends across the truck 95 frame and is provided with two sections 103 and 104 at opposite sides of the truck, the sections being centrally connected by a yoke 105 which permits the saw 90 to pass transversely across the carriage through the central slot provided between the two sections. The carriage is fed toward and away from the saw 90 by hand wheels 106 connected by rods 107 to pinions 108 arranged to travel on 100 rack bars 109 supported on the upper surface of the two angle bars 61.

Electric current for the motor 64 is led to the truck through trolley poles 110 of which there are two provided so that it is not necessary to swing the trolley pole 110 around when the direction of movement of the truck is reversed. The current for the motor 64 passes through a controller 111 mounted on the rear portion of the bed plate 56 which forms a platform for the operator 115 and affords space for carrying any equipment desired.

At the forward end of the truck the plates 58 and 59 partially enclose a space in which mine props 112 are carried. The space is 120 wide enough to accommodate two tiers of props one at each side of the machine, as illustrated in Fig. 6, and the saw carriage 102 is made of proper size and shape to accommodate one of the mine props in either end thereof so that it may be presented by the carriage to the saw 90 when it is desired to shorten the prop by cutting off a portion of its end.

The mechanism for hanging the trolley 125

wire from which power is derived for operating various portions of the apparatus used in connection with the mining process is illustrated in Figs. 17, 18 and 19. This mechanism is carried on the truck wheels 115, the rear wheels being provided with springs 116 and the front wheels being journaled directly in supports 117 on which the casing for the reel is mounted. The truck body 10 comprises a platform 118 which carries a motor 119 and a bearing sleeve 120 in which an upright shaft 121 is journaled carrying a gear 122 arranged to mesh with a pinion 123 driven by the motor 119. A reel 124 on which the trolley wire 125 is wound is journaled on the upper portion of the shaft 121 and carries on its lower face an internal spur gear 126. A gear wheel 127 meshes with the gear 126 and is carried on a shaft 20 journaled in a bearing 128 supported on the platform 118. The lower end of the shaft which carries the gear wheel 127 is provided with a brake 129 operated by a hand lever 130. The gear 127 is driven from the motor 25 119 through a pinion 131 on the shaft 121. Two sets of arms 132 are pivotally mounted to extend downwardly from the platform 118 and carry a pair of skids 133 at their lower ends. The arms 132 may be swung 30 vertically relatively to the truck platform by a hand wheel 134 secured to a shaft 135 journaled in bearings 136 and provided with worms 137 which mesh with worm gears 138 connected with the arms 132 so that when 35 the hand wheel 134 is rotated the arms 132 are swung upwardly or downwardly depending upon the direction of rotation of the hand wheel and thus the skids 133 may be raised or lowered into or out of engagement 40 with the surface of the mine floor. The skids 133 are preferably provided with a pair of screw jacks 139 which may be brought into engagement with the roof of the mine chamber to hold the truck firmly 45 in place.

In hanging the cable 125 it is secured to the mine props very close to the roof of the mine chamber, and in order that the cable may run freely from the reel 124 the axis 50 of the reel is tilted slightly from the vertical, as shown in Figs. 18 and 19 so that the trolley line 125 will extend from the reel at right angles to its axis, as shown in Fig. 21. A guide for the trolley wire as it is wound 55 onto and off of the reel 124 is shown at 140 in the drawings and is free to slide in a slot 141 in the reel casing so that the trolley wire may accommodate itself to the position of the windings on the drum as they move back 60 and forth across its surface. An insulating sleeve 142 is provided for the trolley wire 125 where it leaves the winding drum, said wire preferably extending for a considerable distance from the rear of the drum, as 65 shown in Fig. 21. This insulating sleeve

may consist of a section of rubber tubing surrounded by a flexible metal armour (Fig. 23) to protect the rubber from wear. The sleeve is firmly secured to the guide 140 and the wire travels through the sleeve as it is wound onto and off of the winding drum 124.

In operating the various parts of the mechanism described, the truck carrying the trolley drum is run into the mine chamber along the track supported on its wheels 115. It is then lifted from the track and set at one side of the chamber, as shown at I in Fig. 1 of the drawings. This trolley line truck may remain within the mine chamber at all 70 times during the various operations in the chamber and need not be moved into and out of the chamber as are the other portions of the mining mechanism. The rear end of the trolley wire 125 is connected with a 75 source of electrical current and the wire itself is hung upon the mine props 112 which are arranged at the side of the tracks 32 as the mining progresses. The forward end of the trolley line remains wound about the 80 drum 124 and is held taut by the brake 129. The insulation 142 protects the men operating at the forward end of the mine chamber from electrical shocks by contact with the wire 125. After a room has been cleared by 85 one of the loading machines G of material previously undercut and blasted down, the trucks 35 and 36 are run into the chamber, being propelled by the motor 64 and when the truck 35 has come to a point adjacent 90 the forward end of the track previously laid in the mine chamber, the cable 85 is unwound from the drum 78 and carried forwardly to a point adjacent the front wall of the mine chamber where it is passed about a 95 pulley anchored in the chamber in any suitable manner and the hook 88 is brought backwardly and fastened to one of the track sections carried by the truck 35. The cable is then wound on the drum 78 and the track 100 section will be drawn forwardly over the plate 49 from the truck 35 into position to form a continuation of the mine track. When the track section has thus been positioned, it is secured in place and is ready to 105 carry the various machines for further operation in the mine chamber. The end of the cable 85 is next secured to the eyes in the front end of the skids 133 which carry the trolley line wheel 124 and the trolley line 110 truck is then drawn forwardly over the surface of the mine floor on the skids 133 to unwind an additional section of trolley line. The jacks 139 are of course released before 115 the forward movement of the trolley line truck. During the forward movement of the trolley line truck the brake 129 is kept set sufficiently hard to produce the required tension in the trolley line 125. When the truck has been brought to its new forward 120 125 130

position the jacks 139 are again secured in place to maintain the tension on the trolley line and additional supports for the trolley line are secured to the mine props in the rear 5 of the insulating sleeve 142. Additional props 112 may now be taken from the truck 36 and placed in position along the side of the track. The mine chamber is likely to vary in height at different positions and 10 props 112 of maximum required length are carried by the truck and are shortened by the saw 90 to proper lengths to suit requirements of the different positions in the mine chamber. After these operations have been completed 15 the trucks 35 and 36 are again run out of the room which is now in condition for a second operation of undercutting, blasting and loading. The motor 119 on the trolley line truck is used for winding up the line 20 after the room has been worked out to its full extent and it is desired to remove the trolley line from the chamber.

I claim:

1. In mining apparatus, the combination 25 with a pair of trucks, of means for coupling said trucks together, means adjustable in elevation and carried at one end of the forward truck in position to guide track sections onto and off said forward truck, and 30 rope-winding mechanism comprising a rope adapted to have its free end connected to a track section while being guided onto or off said forward truck.

2. In mining apparatus, the combination 35 with a wheeled truck having a compartment for transporting mine props while occupying a relatively low position, of a saw on said truck spaced from said compartment and also in a relatively low position with its 40 axis of rotation beneath a plane extending horizontally through the upper edges of the wheels of the truck, a motor on said truck, propelling mechanism connected between the motor and the wheels of said truck, and 45 means between said motor and said saw for driving the latter while a prop is held in approximately horizontal position beneath such upper plane.

3. In mining apparatus, the combination 50 with a truck, of a saw mounted thereon to occupy a position in an upright plane for rotation on an axis beneath the upper plane of said truck, a motor mounted on said truck, driving mechanism between said motor and 55 said saw, and a carrier in which a mine prop may be inserted from one side of the truck and held in transverse position for said saw to cut off one end of said mine prop to adjust its length to fit a predetermined 60 location in a mine chamber.

4. In mining apparatus, the combination 65 with a wheeled truck, of a saw occupying a relatively low position on said truck in an upright plane extending longitudinally of said truck and with its axis of rotation be-

low a plane extending through the upper edges of the wheels of the truck, a motor on said truck, driving connections between said motor and said saw, a holder for mine props, and means for moving said holder relative- 70 ly to the saw to effect the cutting off of the ends of the mine props to fit predetermined positions in the mine chamber.

5. In mining apparatus, the combination 75 with a wheeled truck, of a saw mounted thereon with its axis of rotation extending horizontally beneath a horizontal plane extending through the upper edges of the wheels of said truck, a motor mounted on said truck, driving mechanism between said 80 motor and said saw, a double carrier for receiving a mine prop from either side of the truck to hold said prop in transverse position for said saw, to cut off one end thereof, to adjust its length, to fit a predetermined 85 position in the mine chamber, and mechanism operable from either side of the truck for feeding the carrier toward the saw.

6. In mining apparatus, the combination 90 with a pair of trucks, of means for coupling said trucks together, means adjustable in elevation and carried at one end of the forward truck in position to guide track sections onto and off said forward truck, and 95 rope winding mechanism on the other truck and comprising a rope adapted to have its free end connected to a track section and intermediate portion guided at an anchorage distant from the truck.

7. In mining apparatus, the combination 100 with two truck sections coupled together, one truck section being adapted to transport track sections in stacked relation, of equipment on the other truck section for moving track sections toward the forward 105 end of the mine track, and mechanism adjustable in elevation for guiding an uppermost track section from its stacked position.

8. In mining apparatus, the combination 110 with a carriage comprising a plurality of truck sections pivotally connected together by a coupling member, one of said truck sections being provided with a body for supporting a mine track section, of equipment carried by the other truck section for moving said track section of the truck section on which it is supported, and mechanism supported by the latter truck section in 115 spaced relation with the ground of the mine track and in position to guide the said track section toward the space beyond the end of the mine track.

9. In mining apparatus, the combination 120 with a carriage comprising a pair of trucks pivotally connected together by a coupling member, the forward truck being adapted to carry track sections in stacked relation, of 125 rope winding mechanism on the rear truck and comprising a rope adapted to have its free end connected to the respective track 130

- sections to pull the same onto or off the forward truck, a guide plate for directing the track sections onto or off the forward truck, and means for mounting said guide plate on the forward truck for adjustment in elevation corresponding to the elevation of the uppermost track section on the forward truck.
10. In mining apparatus, the combination with a truck having a magazine to support a plurality of mine props laid horizontally and extending transversely to the path of travel of said truck along a mine track, and means on said truck adjacent said magazine for cutting off the ends of said props individually while occupying a position on said truck transverse of the mine track to secure props of varying lengths to fit different positions in the mine chamber.
15. In mining apparatus, a truck having a compartment for transporting a plurality of mine props, a motor on said truck, and a saw occupying a relatively low position near said compartment on said truck in an upright plane extending longitudinally of said truck and connected to said motor to be driven thereby for severing said props individually into various lengths.
20. In mining apparatus, a truck having a compartment for transporting mine props, a motor on said truck, a saw on said truck arranged to be driven by said motor, and a saw carriage arranged to hold one of said mine props and to move said prop into engagement with said saw to cut said prop into a proper length to be used in a mine chamber.
25. In mining apparatus, the combination with a truck having a compartment for transporting mine props while occupying a relatively low position, of a saw on said truck spaced from said compartment and also in a relatively low position, a motor on said truck, propelling mechanism connected between said motor and the wheels of said truck, and means between said motor and said saw for driving the latter while a prop is held in approximately horizontal position beneath the upper plane of the truck.
30. In mining apparatus, a truck having compartments arranged at each side thereof for supporting a tier of mine props so that such props may be removed from said truck at each side thereof, a saw for severing the ends of said props, and a carriage for receiving said props at each side of said truck and for presenting said props to said saw.
35. In mining apparatus, a truck having compartments at each of the opposite sides thereof for holding mine props, and means on said truck operable from either side thereof for severing portions of the ends from said mine props.
40. In mining apparatus, a truck having compartments at each of the opposite sides thereof for holding mine props, a saw centrally mounted on said truck, a carriage having a section at each side of said truck for receiving props to be cut by said saw, and mechanism operable from either side of said truck for moving said carriage toward said saw to feed a prop supported thereby into engagement with said saw.
45. In mining apparatus, a truck for transporting material into a mine chamber, a motor on said truck, mechanism driven by said motor for propelling said truck into and out of said chamber, a power device carried by said truck and arranged to be driven by said motor for moving material into position in said chamber, and mechanism mounted on said truck and arranged to be driven thereby for preparing material for use in said chamber.
50. In mining apparatus, a truck for transporting mine props into a mine chamber, a motor on said truck, means operated by said motor for propelling said truck into and out of a mine chamber, a winding drum mounted on said truck and arranged to be driven by said motor for moving material in said chamber, and a saw carried by said truck and arranged to be driven by said motor for cutting the props carried by said truck into proper lengths to be used in said chamber.
55. In mining apparatus, a truck having a motor mounted thereon, an axle journaled on said truck and connected with the wheels thereof to drive said wheels, a sleeve journaled on said axle and geared to said motor, a clutch for connecting said sleeve with said axle, a drum mounted on said truck, gearing for driving said drum from said sleeve, and a clutch for connecting said drum with said gearing.
60. In mining apparatus, the combination with a truck, of a saw mounted thereon to occupy a position in an upright plane intermediate the sides of said truck, a motor mounted on said truck, driving mechanism between said motor and said saw, and a carrier in which a mine prop may be inserted from one side of the truck and held in transverse position for said saw to cut off one end of said mine prop to adjust its length to fit a predetermined location in a mine chamber.
65. In mining apparatus, a carriage comprising a pair of trucks pivotally connected together by a coupling member, the forward one of said trucks being arranged to carry a plurality of track sections into and out of a mine chamber while the other of said trucks is arranged to carry a plurality of props into and out of said chamber, a motor on said last-mentioned truck for propelling said trucks, a saw on said last-mentioned truck for regulating the lengths of the props

carried thereby, and a drum on said truck for moving the mine sections onto and off of the forward truck.

22. In mining apparatus, the combination with a reel for holding an electric trolley line wire, of a supporting frame for said reel, a truck separate from said reel and the supporting frame thereof, and winding mechanism on said truck and comprising a 10 rope the free end of which is adapted to be connected to said supporting frame to haul the latter along the mine chamber while said reel pays out said trolley line wire for suspension along said mine chamber.

23. In mining apparatus, the combination with a truck adapted to travel on a mine track, of an electric motor mounted on said truck, propelling mechanism connected between said motor and the wheels of said 20 truck, a trolley line suspended in said mine in position to supply electric power to said motor, a reel on which the forward end of said trolley line is wound, and haulage mechanism comprising a rope winding drum on said truck and a rope extending from said drum and adapted to have its free end connected to haul said reel to new forward positions while said trolley line is paid out by said reel for extension along the mine chamber.

24. In mining apparatus, the combination with mechanism for performing a mining operation and comprising a truck adapted to travel on a mine track, of a trolley line for supplying power to said mechanism, a 30 reel for holding the forward end of said trolley line, means for winding said trolley line onto and off of said reel, and rope winding mechanism mounted on said truck and comprising a rope with its free end adapted to be connected to adjust the position of said reel in accordance with the forward movements of said truck.

25. In mining apparatus, the combination with mechanism for operating in a mine 40 chamber, of a trolley line for supplying power to said mechanism, a reel for holding the end of said trolley line, means for supporting said reel on the floor of a mine chamber, and means carried by said first-mentioned mechanism for moving said reel support in said mine chamber to cause said trolley line to be unwound therefrom.

26. The combination with mechanism for operating in a mine chamber, of a trolley line for supplying power to said mechanism, means for supporting said line in said chamber, a reel for holding the end of said line, a wheeled truck for transporting said line into and out of said chamber, means for supporting said truck on the floor of said chamber independent of the wheels thereof, and means on said first-mentioned mechanism for moving said truck along the floor of said chamber to cause the trolley line to be unwound therefrom.

27. In mining apparatus, the combination with mechanism for operating in a mine chamber, of a trolley line for supplying power thereto, means for supporting said trolley line in said mine chamber along the 50 path of travel of said operating mechanism, a reel for holding the forward end of said trolley line, a wheeled truck for transporting said reel into and out of said mine chamber, means for supporting said truck on the floor 55 of said mine chamber independently of the wheels of said truck, means carried by said operating mechanism for moving said supporting means in said mine chamber to cause the trolley line to be extended by being paid out from said reel, a brake for holding said trolley line taut during such paying out thereof, and mechanism for anchoring said truck in said mine chamber after being adjusted to forward positions.

28. In mining apparatus, the combination with a reel for holding electric wire, of a portable supporting frame for said reel, and winding apparatus distant from said reel and comprising a rope the free end of which 60 is adapted to be connected to said supporting frame to haul the latter along the mine chamber while said reel pays out said wire for use in the mine chamber.

29. In mining apparatus, the combination with a reel for holding electric wire, of a portable supporting frame for said reel to hold the latter with its axis of rotation inclined forwardly in an upward direction, and rope-winding mechanism comprising a 70 rope having the free end adapted to be connected to said frame to haul the latter along the mine chamber while the reel pays out said wire.

30. In mining apparatus, the combination of a truck, of a saw occupying a relatively low position on said truck in an upright plane extending longitudinally of said truck, a motor on said truck, driving connections between said motor and said saw, a holder 80 for mine props, and means for moving said holder relatively to the saw to effect the cutting off of the ends of the mine props, to fit predetermined positions in the mine chamber.

31. In mining apparatus, the combination with a wheeled truck, of a motor on said truck, a saw mounted on said truck for rotation on an axis below a plane extending through the upper edges of the wheels of the truck, driving connections between said motor and said saw, and means for holding a mine prop below such plane and directing it to said saw to cut off one end of said mine prop.

32. In mining apparatus, the combination with a wheeled truck, of a motor on said truck, a saw occupying a position intermediate the sides of said truck in a plane extending longitudinally of said truck with its 130

axis of rotation below a horizontal plane extending through the upper edges of any pair of wheels of said truck, and means for receiving a mine prop from either side of the truck to have its inner end cut off by said saw.

33. In mining apparatus, the combination with a truck, of a saw mounted thereon to occupy a position in an upright plane intermediate the sides of said truck, a motor mounted on said truck, driving mechanism between said motor and said saw, a double carrier for receiving a mine prop from either side of the truck to hold such prop in transverse position for said saw, to cut off one end thereof, to adjust its length, to fit a predetermined position in the mine chamber, and mechanism operable from either side of the truck for feeding the carrier toward the saw.

34. In mining apparatus, the combination with a truck having forward compartments arranged to receive tiers of mine props, of propelling mechanism for the truck, a platform at the rear end of the truck for the motorman, and a track extending from the rear end of the platform on an upward incline to a predetermined elevation and then horizontally to said compartments.

35. In mining apparatus, the combination with a truck having means at one end for receiving a plurality of mine props for transportation, of a motorman's platform at the rear end of said truck, a controller on said platform, propelling mechanism for said truck, and reinforcements extending from the rear end of the platform to the forward end of the truck.

36. In mining apparatus, the combination with a truck, of means connected to one end of said truck for receiving a plurality of mine props for transportation, a platform extending from the other end of said truck, means mounted on said truck for sawing off ends of said props, to enable the latter to be fitted in predetermined locations in the mine, and means extending from the rear end of the platform to the forward end of the prop

receiving means to assist in supporting the latter and said platform and prevent sagging thereof.

37. In mining apparatus, the combination with a truck, of two compartments at the forward end of said truck, a platform at the rear end of said truck, propelling mechanism for the truck, sawing apparatus mounted on the truck, and reinforcing mechanism extending from the forward ends of said compartments rearward longitudinally of said truck to the rear end of said platform.

38. In mining apparatus, the combination with a truck, of a magazine at one end thereof for receiving mine props, and means extending rearwardly from said magazine to the rear end of said truck, to enable the rolling of mine props forward or from said magazine along the top of the truck.

39. In mining apparatus, the combination with mechanism for operating in a mine chamber, of a wire for supplying power to said mechanism, a reel for said wire, a frame for supporting said reel, transporting wheels for said frame, and means carried by said frame for engaging the ground independently of said wheels and anchor said frame between the roof and floor of a mine chamber.

40. In mining apparatus, the combination with mechanism for operating in a mine chamber, of a wire for directing power to said mechanism, a reel for said wire, a frame for supporting said reel, transporting wheels for said frame, skids connected to said frame, roof jack mechanism for anchoring said skids between the floor and roof of the mine chamber, and means comprising worm gearing for lifting the wheels off the ground while maintaining said skids rigidly connected to said frame and to said roof jack mechanism while said wire is wound on or unwound from said reel.

In testimony whereof I have signed my name to this specification on this 12th day of September, A. D. 1918.

EDMUND C. MORGAN
